PRESSURE GAUGE

Clarence Wantz and Richard K. Engholdt, Milwaukee, Wis., assignors to Erie Manufacturing Company, Milwaukee, Wis., a partnership consisting of H. F. Alfery and Rube E. Wagner

Application May 20, 1944, Serial No. 536,510

6 Claims. (Cl. 73—411)

1

This invention relates to improvements in pressure gages.

Accurate calibration of pressure gages is obtained by adjusting the rate of movement of the indicator hand relative to the movement of the manometer or pressure responsive element. Adjustment of the initial relative position between the finger of such hand and the pressure responsive device must also be made to obtain zero setting. Such adjustments have been accomplished by manually bending and permanently distorting metal connecting linkage and lever arms comprising the motion transmission means of the device. However, speed and accuracy of calibration are difficult to obtain in this way.

One of the objects of this invention is, therefore, to provide a pressure gage which may be easily, quickly and accurately calibrated, without distortion of the working parts.

Another object of the invention is to provide a pressure gage in which back lash and lost motion in the motion transmission means is eliminated or reduced to a minimum.

A further object of the invention is to provide a pressure gage which may be readily constructed from machine parts.

The foregoing objects are accomplished by providing a connection between the pressure responsive device and the pivotally mounted indicator hand which will keep the working surfaces under pressure contact while the parts are in motion thereby eliminating back lash and lost motion, and including a frictionally maintained relatively movable element to vary the distance between the pivotal axis of the hand and said connection. The position of said element can be quickly and accurately regulated to make small adjustments in the length of the lever arm by which the motion of the pressure responsive device is transmitted to the indicator hand. The indicator hand is also provided with an offset portion between the hub and finger. This offset portion is of such proportion that it may be easily deformed to make sufficient changes between the relative positions of the hub and the finger to obtain a zero setting.

With the foregoing and other objects in view, developed by the following description, the invention consists in certain novel advantageous structural organizations and features, as well as combinations and sub-combinations, as more fully explained hereinafter and specified by the following claims.

Referring to the accompanying drawings forming a part hereof,

2

Figure 1 is a top plan view of a pressure gage comprising the invention;

Figure 2 is a fragmentary, greatly enlarged top plan view of the pivotally mounted eccentric sleeve, hub portion of the indicator hand, and the wire link connecting the end of the Bourbon tube and the hub of the indicator hand;

Figure 3 is a fragmentary view in side elevation taken from the line 3—3 of Figure 2;

10 Figure 4 is a sectional view taken on line 4—4 of Figure 2;

Figure 5 is a sectional view taken on line 5—5 of Figure 1;

15 Figure 6 is a view partly in section and partly in side elevation of the eccentric sleeve comprising a part of the mounting for the indicator hand; and

Figure 7 is a top plan view of the eccentric sleeve of Figure 6.

20 Referring in greater detail to the drawings, there is illustrated a pressure gage embodying the invention. In general, the pressure gage comprises the following elements: a body 10 on which the other elements are mounted; a Bourbon tube 20, the free end of which has limited motion under the influence of changes in pressure in the pressure to be measured; an indicator hand 30 which is carried by a pivotally mounted eccentric sleeve 40; a wire link 50 which transmits the substantially lineal motion of the free end of the Bourbon tube 20 to the indicator hand 30 at a point removed from its pivotal axis to cause it to have angular movement; a dial 60, provided with a scale over which the finger of the indicator hand 30 travels to indicate selected pressures of the pressure being gaged; and a cover member 70 having a sight window enclosing the working parts.

25 The construction of the body member 10 is such that it may be readily fabricated as a machine part rather than a casting. The main portion has depending centrally therefrom a threaded nipple 11. The nipple 11 is adapted to fit in standard fittings customarily used in connecting pressure gages to the pressure to be gaged. Also 30 centrally located with respect to the main portion is an upwardly projecting cylindrical boss 12. The boss 12 and nipple 11 are axially aligned, and a drilled out passageway 13 extends along their axis from the bottom of the nipple 11 to approximately the center of the boss 12. As is shown in Figures 1 and 5, another drilled out passageway 14 extends substantially radially from the passageway 13 to the outer side of the boss 12. The 35 passageway 14 is provided with a counter-bore

15 for receiving and holding the tubularly shaped end of the Bourbon tube 20. A flange 16 extends around the periphery of the main portion to form a lip for engaging the cover member 10 to retain it in proper position. The main portion is also provided with a drilled hole 17 which receives and holds the pivot pin 41 upon which the eccentric sleeve 40 pivots, and a tapped hole 18 into which a screw may be threaded to hold the cover 10 in place. It should be noted that the body member 10 is preferably turned from hexagonal stock which permits the main portion to also act as a nut by which the entire gage may be securely threaded into place. However, it may be cast instead of turned and any irregular shape may be conveniently used to provide a gripping surface.

The Bourdon tube 20 in some respects is similar to that generally known to those skilled in the art. Because of the central location of the boss 12 with respect to the body 10, the tube 20 is provided with a bend 21, so that the round or unflattened end 22 will be in alignment with and securely held within the counter-bore 15 while the balance of the tube is positioned around the outside of the boss 12. The free end of the tube 20 has rigidly secured thereto a U-shaped clip 24 which acts as an anchor for the link 50. To this end, its upper end (see Figures 3 and 4) extends above the confines of the tube and is provided with a notch 25 in which the wire link 50 may rest and be held during the application and solidifying of the solder 26, or other material or method used to rigidly join the clip 24 and wire link 50.

The movement of the free end of the tube 20 under changes in pressure is relatively small, and it cannot readily be visually distinguished. It is, therefore, necessary to provide an indicator hand 30, the finger 31 of which has a range of movement considerably greater than the movement of the free end of the tube. The dial 60 with its scale of selected pressures is secured to the face of the boss 12 in such a manner that the scale and the tip of the finger 31 are in register as the indicator hand swings from one end of the scale to the other as the pressure to be measured increases from a selected low limit to a selected high limit.

To accomplish such swinging motion, the indicator hand 30 is pivotally mounted and the free end of the tube 20 is connected to the hand at a point near the pivotal axis of the hand (pivot 41) by the wire link 50. Thus small substantially lineal movement of the free end of the tube 20 acts through a relatively short lever arm to cause the finger 31 to have relatively large angular, or swinging movement. It will be seen, therefore, that small changes in the length of the small lever arm will cause the finger 31 to vary its rate of movement with respect to the movement of the free end of the tube. This fact is utilized to effect a calibration of the gage in the final testing step of manufacture.

Therefore, the means for pivotally mounting the indicator hand 30 also includes means for making small adjustments in the length of the small lever arm. The pivot pin 41, which has a drive fit in the drilled hole 17, provides the axis of the pivotal mounting. An eccentrically formed sleeve 40 rotatably fits on the pin 41. This sleeve (shown in detail in Figures 6 and 7) is preferably formed from hexagonal stock. It has a lower portion 42 which is turned down concentric with the longitudinal axis of the stock. An intermediate portion 44 is not turned down and

retains its hexagonal shape to form a nut by which the sleeve may be held for purposes of making adjustments. Immediately above the nut portion 44 there is a cylindrical spacer 45, the longitudinal axis of which is offset from the longitudinal axis of the stock. This spacer carries cylindrical support 46 for the indicator hand 30. The longitudinal axis of the cylindrical support 46 is also offset from the longitudinal axis of the stock. The sleeve 40 is provided with a longitudinal bore 43 co-axial with the axis of the stock. This bore provides a bearing between the sleeve 40 and shaft 41 by which the sleeve is rotatively mounted on the body 10. The indicator hand 30 has a hub 32 provided with a bore into which the cylindrical support 46 tightly fits. The bottom of the hub rests against the shoulder formed by the juncture between the spacer 45 and the cylindrical support 46. In order to thusly hold the hub 32, the perimeter of the top surface of the cylindrical support 46 is swaged over the hub 32. The tool for such swaging may be guided by the stud 47, formed on the cylindrical support 46. The fit between the cylindrical support 46 and the bore of hub 32 is sufficiently tight to cause the hub and the sleeve to rotate as a unit about the pivot pin 41. However, if the hub 32 is held, the sleeve 40 may be rotated relative thereto by exerting sufficient rotative pressure on the nut 44. The hub 32 is also provided with an aperture 34 for rotatively receiving the down-turned end of the wire link 50 to form motion transmission means therebetween. The distance between the center of the aperture 34 and the axis of the pivot pin 41 constitutes the length of the small lever arm hereto discussed. A finger 31 is connected to the hub 32 by an offset portion 33. The offset portion 33 is sufficiently long to permit it to be readily twisted to effect zero adjustment. The transmission of motion from the Bourdon tube 20 to the indicator hand 30 is accomplished by a wire link 50 which has a turned-down portion 51 rotatively fitting within the aperture 34. The turned-down portion 51 is of sufficient length so that when its end rests against the upper surface of the nut portion 44, the curved portion between the main body of the link and the down-turned portion 51 will be held out of engagement with the aperture 34, thus preventing the possibility of friction or binding action between the hub 32 and the link 50. As is shown in Figures 2, 3 and 4, the wire link 50 has its other end loosely resting in a notch 25 formed in the clip 24. After proper adjustments have been made during the assembly of the device, this end of the link is rigidly anchored in place in the clip 24.

A cover or housing 10 fits over the working parts of the gage. It comprises an inverted metal cup-shaped member, the skirts or sides of which fit within the flange 16. One-half of the top of the cover 10 is preferably cut away to provide a window substantially in registry with the dial 60. A sheet of transparent material 71 is fitted with the cover to close the opening or cut away portion. This sheet is held in place by a smaller inverted cup-shaped holding member 72 telescoped within the cover 10 and held in place by a pressure fit or other known means. A screw 73 passes through holes in the top of the cover 10 and holding member 72 and threads into the tapped hole 18. A spacer 74 is positioned over and held on the screw to prevent undue distortion of the top of the cover 10 and to prevent disassembly of the screw from the cover when the cover has been removed. After the gage has been assembled, with the ex-

ception of rigidly securing the link 50 to the clip 25, it is calibrated and tested. The gage is placed on a manifold where it is subjected to selected known pressures ranging from zero (i. e. atmosphere) to ultimate limit for which it is designed. The Bourdon tube is first allowed to assume its normal position when influenced by zero pressure (i. e. atmosphere). The indicator finger 31 is then moved to the zero position, as indicated in Figure 1. This motion is possibly accompanied by a relative sliding between the wire link 50 and the clip 24. While in this position the wire link 50 may be deflected from its normal straight line, as shown in Figure 2, to the slightly sprung position shown in Figure 1, or the reverse thereof. The notch 25 acts as a fulcrum for this deflection. While in this deflected state, it is preferable to apply solder to the wire 50 and the clip 24 and permit it to solidify while the wire is so deflected. Thus a rigid connection is established between the resilient link 50 and the end of the Bourdon tube 20. However, other means than soldering may be used to make this rigid connection. The important thing is to deflect the wire link 50, and then, while so deflected, make its connection to the tube rigid. Thus the link could be brazed or spot welded to the clip or the sides of the clip pressed and tightly formed around the link to rigidly hold it. Thereafter, when the deflecting tension is removed, the wire is biased and continually has the effect of maintaining the bearing surfaces between the pivot pin 41 and the sleeve 40 as one unit, and the aperture 34 and the downturned portion 51 as another unit, in close surface-to-surface contact. Slight tension may be also exerted by the wire 50 downwardly against the upper surface of the nut 44, thus maintaining the sleeve 40 properly in place on the pivot 41. This eliminates all back lash and lost motion between the parts. Even if the wire 50 is not so deflected prior to making the rigid connection, an important result is still obtained by the step of making the rigid connection after the wire has been loosely assembled in place. This result is the insurance of a connection having minimum frictional losses. This is accomplished because the turn-down portion 51 of the wire link 50 is properly aligned in the aperture 34 by the action of the close tolerance fit therebetween, and this proper alignment is not thereafter disturbed by subsequently rigidly anchoring the link to the tube 20.

The Bourdon tube is next subjected successively to increasing known pressures. As the tube expands from one known pressure to another, the resultant movement of the finger 31 should be such as to move it the same distance as exists between those markings on the scale of the dial 60 which corresponds with such known pressures. If this does not occur, it is necessary to adjust the rate of movement of the indicator hand 30 to the rate of movement of the free end of the Bourdon tube 20. In this device such correlation is effected by increasing or decreasing the distance between the longitudinal axis of the pivot pin 41 and the center of the aperture 34, heretofore described as the relatively short lever arm by which the lineal movement of the link 50 is translated to angular movement of the indicator hand 30. As the cylindrical support 46, upon which is carried the hub 32, is eccentric to the axis of the pivot pin 41, relative rotation between the hub 32 and the sleeve 40 causes the length of such lever arm to vary in relatively small amounts. If the distance moved by the finger is too short, the 78

lever arm must be decreased to increase the rate of movement. If such distance is too long, the lever arm is increased in length. To accomplish this relative movement, the hub 32 is held while the sleeve is rotated relatively thereto by applying turning pressure on the nut 44.

After calibration of rate of movement has been accomplished and it is found that the finger 31 did not exactly register with each marking on the scale, a slight adjustment may be made by twisting the offset portion 33 on the hand 34. To do this, it is necessary only to deflect the finger 31 in the desired direction while holding the hub 32 stationary. This adjustment does not in any way alter the previously made rate of movement calibration.

Although there is shown and described certain specific embodiments of the invention, many modifications thereof are possible. The invention is not to be restricted except insofar as necessitated by the prior art and by the spirit of the appended claims.

We claim:

1. In a pressure gage, a pressure responsive device having a portion movable under the influence of changes in pressure to be gaged, a pivotally mounted sleeve provided with an eccentrically positioned support, an element of an indicator mechanism provided with a hub, said hub being frictionally engaged by said support whereby said sleeve and indicator element normally pivot as a unit, a link connecting said portion and said hub to transmit motion from said pressure responsive device to said hand, said hub and said support being relatively movable against said frictional engagement to vary the distance between the pivotal axis of said sleeve and the interconnection between said hub and link to adjust the rate of movement of said hand relative to the movement of said pressure responsive device.

2. In a pressure gage, a Bourdon tube, one end of which is movable under influence of pressure to be gaged, a clip on said end having a slot adapted to receive and loosely hold one end of a wire link, a pivotally mounted indicator hand having a hub provided with an aperture to receive another end of a wire link, and a wire link having one end rotatively engaged in said aperture and the other end positioned in said slot, said last mentioned end being held in said slot by solder which has solidified after said wire link has been deflected from its normal position, whereby said wire link acts to convey motion from said tube to said indicator and also pre-stresses all bearing surfaces to prevent back lash and lost motion.

3. In a pressure gage, a pressure responsive element movable under the influence of changes in the pressure to be gaged, a pivotally mounted member provided with an eccentrically positioned hub receiving support, an indicator hand having a hub, said hub being frictionally engaged by said support, whereby said member and hand normally pivot as a unit, a laterally distorted and pre-tensioned wire link connecting said pressure responsive element and said hub whereby the motion of said element causes said sleeve and hand to pivot as a unit, said link by reason of its pre-stress causing all relatively movable connecting and bearing surfaces to remain in close contact to eliminate back lash and lost motion, said hub and said support being relatively adjustable to vary the distance between the point of connection of said link with said hub and the axis of

pivotal movement of said pivotally mounted member.

4. In a pressure gage, a Bourdon tube, one end of which is movable under influence of pressure to be gaged, a clip on said end having a slot adapted to receive and loosely hold one end of a wire link, a pivotally mounted indicator hand having a hub provided with an aperture to receive another end of a wire link, and a wire link having one end rotatively engaged in said aperture and the other end positioned in said slot, said last mentioned end being rigidly secured in said slot while said wire is deflected from its normal position, whereby said wire link acts to convey motion from said tube to said indicator and also prestresses all bearing surfaces to prevent back lash and lost motion.

5. In a pressure gage, a Bourdon tube, an eccentric freely pivotally mounted adjacent said tube, an indicator hand having a hub portion frictionally mounted on said eccentric, said hub portion and said eccentric constituting a crank arm, and a direct connection between the latter and the free end of said tube, movement of said eccentric relative to said hub portion varying the effective length of said crank arm and the rate of movement of said hand relative to that of said tube.

6. In a pressure gage, a Bourdon tube one end of which is movable under influence of changes in pressure to be gaged, an element of an indicator mechanism pivotally mounted to permit swinging thereof in the actuation of the indicator mechanism, a wire link retaining element on said movable end of said tube, a circular bearing aperture in said indicator mechanism element for rotatively receiving a laterally projecting portion of a connecting link, a wire link having one

end bent to form a laterally projecting portion, said portion being rotatively received and guided by said bearing aperture, abutment means spaced from and underlying said aperture for engaging the end of said portion for spacing said link from said aperture whereby the bend between said link and said portion will be restrained from entering said aperture, said link having the end opposite said projecting portion secured to said element while said link is maintained in normally alined position by the guiding action of said bearing aperture, said retaining element and said abutment means.
